Inventor,

George Columb Kennedy.

UNITED STATES PATENT OFFICE.

GEORGE COLVIN KENNEDY, OF WATERLOO, IOWA.

ADJUSTABLE DECORATION FOR SHOES.

Application filed August 15, 1924. Serial No. 732,338.

To all whom it may concern:

Be it known that I, GEORGE COLVIN KENNEDY, a citizen of the United States of America, and a resident of Waterloo, Black Hawk County, Iowa, have invented certain new and useful Improvements in Adjustable Decorations for Shoes, of which the following is a specification.

My invention pertains to adjustable decorations for shoes, and the object of my improvement is to supply an ornamental device for removable attachment to a boot or shoe, constructed flexibly and shaped to be easily conformed to curved outer surfaces of a shoe and having means for anchoring it in position, the device also having means for allowing it to be conformably adjustably mounted upon shoes of different sizes and shapes.

A further object is to combine with this kind of shoe decoration additional parts connected thereto adapted to enhance the decorative effect thereof to the eye.

Another object is to combine with the device when desired elements connected thereto and suitable to be positioned upon the ankle above the shoe for decorative purposes.

These objects I have accomplished by the means which are hereinafter described and claimed, and which are illustrated in the accompanying drawings, it being understood that changes in the precise embodiment of invention herein disclosed can be made within the scope of what is claimed without departing from the spirit of the invention.

In the drawings, Fig. 1 is a top plan, as developed upon a plane, of my decorative ornament for shoes, with parts broken away.

Fig. 2 is an under plan view of a shoe, showing the adjustable elastic fastening means used to removably mount said ornament upon the shoe by attachment to the sole thereof. Fig. 3 is a longitudinal section of the ornament shown in Fig. 1, taken on the broken line 3—3 of Fig. 1. Fig. 4 is a perspective view of a pair of my flexible decorative devices mounted upon the shoes of a wearer. Fig. 5 is an under plan view, on a larger scale than that used for the previously mentioned figures, of an ankle decorative device combined with one of the flexible shoe ornaments. Fig. 6 is a perspective view of the combined shoe and ankle ornaments as mounted upon the shoes of and over the ankles of a wearer.

Similar numerals of reference denote similar parts throughout the several views.

My ornamental device for shoes consists of a piece of flexible material shaped appropriately to fit smoothly upon and across the upper or vamp of a shoe, and may be of cloth, leather or other material which can stretch yieldingly or elastically as shown in Fig. 4, or may be of bendable soft metal as shown in Figs. 1 and 3, in the latter case being cut and shaped to have some places narrower than others or otherwise so weakened as to yield conformably without buckling or creasing when fitted manually and adjustingly upon a shoe, or upon shoes of different sizes or shapes.

The device of said Fig. 1 exemplifies this idea as used with a soft metal plate, and the ornamental pattern may be varied. As shown, the plate is made wider in the middle and gradually diminished toward opposite ends on such a curve as to best fit it across and contractingly upon the arch of a foot over the vamp of a shoe 25 with the extremities of the plate brought approximately to the opposite edges of the sole 16 between the heel and the main part of the sole. The plate 1 is preferably shaped with a narrow longitudinal medial strip 2 for greater relative flexibility than the projecting parts 3 or the middle part 4. The following means is provided by which to detachably fasten or anchor the opposite diminished extremities of the plate 1 to the upwardly arched part of the sole 16 immediately anterior to the front wall of the heel. A headed nail 7 is fixed in that part of the sole 16 and a short strip of elastic band 5 has its opposite ends stitched or otherwise secured to the ends of the plate 1 as by the holes 8. On the middle of the band 5 is fastened a looped eye 6 which may be detachably mounted upon the nail 7 under some tension of the band. The band 5 will stretch elastically to permit of adjustably fitting the plate 1 upon shoes of different sizes or to yield to movements of the foot in walking.

To produce a relief ornament, additional and smaller plates 10 and 12 may be fastened upon the plate 1 as by a split rivet 14. The plates 10 and 12 may have their margins divided to supply projections 11 and 13 respectively to represent the petals of a flower which, together with other parts of the plate 1, may be ornamented as by gilding

or enameled colors for decorative effect. The middle part 4 of the plate 1 beneath the plates 10 and 12 may be shaped also with petals 9 to thus build up in relief a flower ornament, giving a richer and more natural appearance.

The device 1 shown in Fig. 4, being of cloth or leather, may stretch and conform smoothly to the shoe without any need for 10 weakening by cutting out marginal parts and is kept under tension by the elastic band 5 to keep in smooth contact with the vamp of the shoe. The part 1 may have any kind of ornamental decoration as by painted ornaments 26 and 27, or as shown in Fig. 6, a bow or other ornamental element 17 may be mounted thereon, secured by mating fasteners 15 or otherwise.

When desired, a decorative ankle covering 20 may be attached to the part 1 as shown in Figs. 5 and 6. This may be of any shape, but as shown, has a longitudinal middle part 18 and side projections 24, the part 18 lying lengthwise along the front of the ankle 25 of the wearer and the flexible side projections embracing the sides of the ankle or leg and whose tips may be detachably secured together by mating fasteners 22, or otherwise. The said device may be made of any 30 flexible material, preferably soft and yielding such as thin cloth or leather. The lower part thereof may be mounted detachably upon the strip 1 by mating fasteners 21 or otherwise. The device 18 may have a stiffener bar 23 stitched along its under face as at 24 and may have a lining 20 covering the bar. When the bar 23 is made of soft annealed copper or the like, it supports the device 18 flexibly during movements of the 40 leg.

The user can easily mount or demount the part 1 by simply looping the eye 6 upon the nail 7 or separating it therefrom, so that the ornament may be applied to different 45 shoes in turn, or to permit changes of patterns when desired.

Having described my invention what I claim as new, and desire to secure by Letters Patent, is:

50 1. A self-adjusting annular device to embrace a shoe, of which a part is flexible non-extensible and surrounds the upper of the shoe, and another part is elastic to traverse the sole part of the shoe, whereby the device 55 may be passed adjustably around shoes of varying circumferences.

2. A flexible strip of ornamental appearance positioned across the upper of a shoe, means for separably fastening it upon the 60 shoe, and a structure of bendable metal cut with partially separated peripheral portions of an ornamental character and means for fastening said structure upon said strip substantially medially.

3. A strip of soft bendable metal mounted across the upper of a shoe weakened in places to be manually shaped to conform to the curved surfaces thereof smoothly, and means for detachably fastening the ends of the strip under the arch of the shoe.

4. A flexible soft metal plate of ornamental shape mounted across the upper of a shoe, and a smaller flexible soft metal plate fastened upon the first-mentioned plate to have projecting parts which may be bent to 75 present an ornamental shape.

5. A flexible strip mounted detachably across the upper part of a shoe, and another flexible strip connected at one end to the first-mentioned strip and projecting upwardly therefrom toward the ankle of the wearer.

6. A flexible strip detachably secured across the upper of a shoe, and another flexible strip connected at one end medially to the first-mentioned strip and projected angularly therefrom, and means for detachably securing the second-mentioned strip upon the instep and ankle of the wearer.

7. A flexible strip mounted detachably across the upper of a shoe, and another strip of flexible material projecting angularly 90 therefrom upwardly along the ankle of the wearer, and stiffening means connected to the second-mentioned strip to uphold it in position.

8. A flexible member mounted conformably upon a shoe, and another flexible member connected to the first member and having opposite side projections to fit and embrace opposite sides of the ankle of a wearer.

9. A flexible ornamental member mounted upon the upper part of a shoe to project thereabove along the limb of the wearer, and means for holding it conformably upon both.

10. A flexible ornamental member secured yieldingly and conformably upon a shoe to extend toward the ankle of the wearer to be fastened thereupon, and having partially separated parts of an ornamental character.

11. A pair of flexible ornamental members, one secured removably upon a shoe, and the other being fastened detachably upon the first member, to be passed upwardly along the limb of the wearer there to be mounted upon the limb in a desired relation thereto.

12. A bendable ornamental device shaped to be positioned against a leg of the wearer conformably, and fastening means for supporting said device upon the foot of the wearer below separably to thus decorate the leg above the foot and to be self-adjusting to the leg and to its movements.

Signed at Waterloo, Iowa, this 17th day of July, 1924.

GEORGE COLVIN KENNEDY.
